UNITED STATES PATENT OFFICE.

JOHANN PAEHLKE, OF BERLIN, GERMANY.

CONFECTIONERY-BRUSHING MACHINE.

SPECIFICATION forming part of Letters Patent No. 687,542, dated November 26, 1901.

Application filed December 13, 1900. Serial No. 39,716. (No model.)

To all whom it may concern:

Be it known that I, JOHANN PAEHLKE, a citizen of the Empire of Germany, residing in Berlin, Germany, have invented certain new and useful Improvements in Confectionery-Brushing Machines, of which the following is a specification.

This invention relates to brushing-machines for removing flour or the like from confectionery and similar goods. In the manufacture of many kinds of confectionery, as is well known, the same is covered with fine flour, which adheres to the cast pieces and has to be subsequently removed. In machines of this kind heretofore made this removal was effected by means of a tray containing the goods and reciprocating within a closed chamber, so as to bring the goods in contact with suitable brushes. Such machines have the disadvantage, however, that the driving mechanism for the carriage upon which the tray was placed was more or less complicated and was located to a considerable extent within the chamber or chest, and the flour removed from the candy collected upon the mechanism and became soiled by contact therewith, and the mechanism was often clogged and its reliable operation interfered with.

The object of my invention is to construct a machine in which these disadvantages are obviated, and for this purpose the invention consists in the combination, in a confectionery-brushing machine, of a frame, a chest supported by said frame, a carriage guided in said chest, a tray adapted to be supported on said carriage and provided with a perforated bottom, brushes on opposite sides of the path of movement of said carriage and tray, said brushes having bearings mounted outside of the chest, a slide-rod connected with said carriage and guided at one end through said chest, and a power-transmitting mechanism arranged entirely outside of said chest and communicating reciprocating motion to said carriage through the medium of said slide-rod, and also communicating rotary motion to said brushes; and the invention consists, further, in certain other combinations of operative parts, which will be fully described hereinafter and finally pointed out in the claims.

In the accompanying drawings, Figure 1 is

a side elevation, partly in section, of my improved apparatus. Fig. 2 is a vertical transverse section on line 2-2, Fig. 1. Fig. 3 is a vertical longitudinal section, drawn on a larger scale, through the brushes, tray, and carriage; and Fig. 4 is a horizontal section on line 4-4, Fig. 1.

Similar letters of reference indicate corresponding parts.

Referring to the drawings, *a* indicates the frame of my improved machine, on which is mounted the main shaft *b*, which drives the small shaft *e* by means of pulleys *c* and *f* and belt *d*. On the shaft *e* is a crank *g*, which imparts reciprocating motion to a lever *i*, which is pivoted at one end and connected with said crank by a connecting-rod *h*. The opposite free end of the lever *i* is connected by means of a rod *k* with a slide-rod *n*, a roller *l* being mounted on the pivot connecting said rod *k* and slide-rod *n* and said roller being guided between suitable guide-rods *m*. The slide-rod *n* is guided in the rear end of a chest *o*, and within said chest is connected in any suitable manner with a carriage *p*, consisting of an angle-iron frame mounted on rollers *p'* and adapted to be reciprocated longitudinally in the chest *o* upon its guide-rails *a'*, secured in any suitable manner to the sides of the chest. The sprocket-wheel *r* upon the shaft *b* drives by means of a chain *s* and pulleys *t* two pairs of brushes *t*, an upper pair and a lower pair, mounted on the shafts of said pulleys, which shafts extend entirely through said casing, as shown in Fig. 2, and are journaled at their ends at the outside of the casing or chest *o* in bearing-pieces *v*, adjustable in a suitable slotted standard *f'* by the adjusting-screws *w*. The brushes *t* are so located and arranged that the carriage *p* with its tray can be moved through between the upper and lower pairs of brushes, the guide-rails *a'* for the carriage being located slightly above the level of the shafts of the lower brushes, as shown in Fig. 2.

The confectionery upon the carriage *p* is vigorously brushed by the brushes, the upper brushes brushing the upper surface of the candies, while the lower brushes find access to the lower surface of the same through the perforated bottom *b'* of the tray, as shown in Fig. 3. In order to prevent the flour which

is brushed off the confectionery from accumulating in the chamber or settling again upon the goods, a powerful current of air is maintained between the pairs of brushes.

5 This air-current may be produced by means of a bellows F, preferably located upon the upper part of the chest and operated by a connecting-rod g', pivoted to the crank g. Atmospheric air is sucked in by the bellows and 10 is delivered from the same through the pipe y and nozzle z into the upper part of the chest between the upper pair of brushes. From the lower portion of the chest opposite said nozzle z and the lower pair of brushes extends 15 an outlet-pipe A, through which air charged with flour is drawn from the interior of the chest and delivered into a separating-chamber E, having at its upper part a flour-screen B. The flour cannot pass the screen, but 20 collects in the lower part of the chamber and can be removed from time to time by first removing the door C. From the upper part of the separating-chamber—i. e., that part protected by the screen B—leads an exhaust-pipe 25 D to an exhaust-fan D', coöperating to produce a strong current of air through the apparatus during the cleaning operation, by which the flour is drawn off as fast as removed from the confectionery. The fan D' 30 is preferably operated from a pulley d' on the main shaft b by means of suitable belt-and-pulley transmission over the counter-shaft e'.

Having thus described my invention, I claim as new and desire to secure by Letters 35 Patent—

1. In a confectionery-brushing machine, the combination of a frame, a chest supported by said frame, a carriage guided in said chest, a tray adapted to be supported on said 40 carriage and provided with a perforated bottom, brushes within said chest on opposite sides of the path of movement of said carriage and tray, said brushes having bearings mounted outside of the casing, a slide-rod 45 connected with said carriage and guided at one end through said chest, and a power-transmitting mechanism arranged entirely outside of said chest, and communicating reciprocating motion to said carriage through 50 the medium of said slide-rod, and also communicating reciprocating motion to said brushes, substantially as set forth.

2. In a confectionery-brushing machine, the combination of a frame, a chest supported 55 thereby, a carriage guided in said chest, a tray adapted to be supported on said carriage and provided with a perforated bottom, brushes within said chest on opposite sides of the path of movement of said carriage, said 60 brushes having bearings mounted outside of the casing, a slide-rod connected with said carriage and guided at one end through said chest, a power-transmitting mechanism arranged entirely outside of said chest and communicating reciprocating motion to said carriage through the medium of said slide-rod, 65

and also communicating rotary motion to said brushes, a bellows, means for operating the same, a pipe connecting said bellows with the top of said chest adjacent said brushes, and 70 an outlet-pipe leading from said chest, substantially as set forth.

3. In a confectionery-brushing machine, the combination of a frame, a chest supported thereby, a carriage guided in said chest, a 75 tray adapted to be supported on said carriage and provided with a perforated bottom, brushes within said chest on opposite sides of the path of movement of said carriage, said brushes having bearings mounted outside of the casing, a slide-rod connected with said carriage and guided at one end through said chest, a power-transmitting mechanism arranged entirely outside of said chest and communicating reciprocating motion to said carriage through the medium of said slide-rod, 80 and also communicating rotary motion to said brushes, a bellows, a pipe connecting said bellows with the upper part of said chest adjacent said brushes, a separating-chamber, an 85 outlet pipe connecting said chest and separating-chamber, an exhaust-fan, an exhaust-pipe connecting said separating-chamber and exhaust-fan, and means for operating said bellows and exhaust-fan, substantially as set 90 forth.

4. In a confectionery-brushing machine, the combination of a frame, a chest supported thereby, a carriage guided in said chest, a 100 tray adapted to be supported on said carriage and provided with a perforated bottom, brushes arranged in pairs within said chest on opposite sides of the path of movement of said carriage, said brushes having bearings mounted outside of the casing, a slide-rod 105 connected with said carriage and guided at one end through said chest, a power-transmitting mechanism arranged entirely outside of said chest and communicating reciprocating motion to said carriage through the medium 110 of said slide-rod, and also communicating rotary motion to said brushes, a bellows, means for operating the same, a pipe connecting said bellows with the upper part of the chest between the brushes of the upper pair, an outlet-pipe leading from said chest between the 115 brushes of the lower pair, a separating-chamber connected with the outer end of said outlet-pipe, a perforated partition in said separating-chamber, an exhaust-fan, an exhaust-pipe 120 connected with said fan and with said chamber at the opposite side of said perforated partition from the outlet-pipe, and means for operating said exhaust-fan, substantially as set forth.

In witness whereof I have hereunto set my hand in presence of two witnesses.

JOHANN PAEHLKE.
